OXYGEN SENSOR

Stephens N. Sato, San Diego, Calif., assignor to
Ivac Corporation, San Diego, Calif.

Filed Nov. 1, 1971, Ser. No. 194,777

Term of patent 14 years

Int. Cl. D24—01, 99

U.S. Cl. D83—1

FIG. 1 is a perspective view of an oxygen sensor showing my new design;

FIG. 2 is a front elevational view of the sensor shown in FIG. 1;

FIG. 3 is a top plan view of the sensor shown in FIG. 1;

FIG. 4 is a left side elevational view of the sensor shown in FIG. 1; and

FIG. 5 is a bottom plan view of the sensor shown in FIG. 1.

I claim:

The ornamental design for an oxygen sensor, as shown.
